UNITED STATES PATENT OFFICE.

LEONARD A. YOUNG, OF DETROIT, MICHIGAN.

LATCH.

1,110,368.

Specification of Letters Patent. Patented Sept. 15, 1914.

Application filed June 12, 1914. Serial No. 844,636.

REISSUED

To all whom it may concern:

Be it known that I, LEONARD A. YOUNG, a citizen of the United States of America, residing at Detroit, in the county of Wayne 5 and State of Michigan, have invented certain new and useful Improvements in Latches, of which the following is a specification, reference being had therein to the accompanying drawings.

- 10 In fitting doors, casings and other like parts which close upon each other, especially in refrigerators, ovens or like places, it is desirable that means be used for yieldingly maintaining the closure against the containing frame in such manner that the point between the two is kept tight regardless of slight variations due to expansion or contraction of the parts from climatic changes and the like.
- 15 This invention relates to a latch and to an arrangement thereof whereby the door or other closure to which it is applied is firmly held yieldingly and tightly against its jamb or casing, such contact being maintained 25 even when the door or frame swells or contracts.

- The invention consists in the matters hereinafter set forth and more particularly pointed out in the appended claims.
- 30 In the drawings, Figure 1 is a view in front elevation of a latch embodying features of the invention showing a striker and catch in closed relation; Fig. 2 is a view in vertical section through the closed latch 35 showing the same applied to a door and door jamb; Fig. 3 is a view in longitudinal section in detail of a casing; Fig. 4 is a view in detail of a bed plate and spring; Fig. 5 is a view in longitudinal section through a 40 modification of the latch showing one of the catch members provided with a thumb piece; Fig. 6 is a view in longitudinal section in detail showing a slight modification of the latch mechanism; Fig. 7 is a view in detail 45 of the spring, latch members and bed plate of the modification; Fig. 8 is a view in transverse section through a spring, bed plate and adjacent parts; Fig. 9 is a view in detail of a striker member that likewise constitutes a handle; Fig. 10 is a view in detail 50 showing a modification of a casing; and Fig. 11 is a view in detail and in section through the modified casing, showing the relation thereof on the latch member.
- 55 Referring to the drawings, an exterior casing 1 that is formed or struck up of sheet

metal or otherwise made of suitable material, has a pair of projecting guide lugs 2 on its front face whose adjacent convergent faces 3 terminate at the margins of a slot indicated at 4 in the front wall. The flanged base of the casing is adapted to be applied to the casing or jamb of a door or the like on which the latch is mounted, and is arranged to retain a bed plate 6, screws or 60 other fastening means that pass through openings 7 in the casing flange and registering slots 8 in the plate holding the parts in position.

A U-shaped spring strip 9 is secured as 70 by inturned ears 10 or the like to the base plate within the casing the oppositely disposed arms having longitudinally disposed slots and the resultant center tongue of each arm being shortened and inrolled as indicated at 11 for a bearing. A pair of oppositely disposed latch plates 22 have recessed outer ends which bear against the inrolled tongue portions 11 of the springs, and abutting outer end faces which are in rolling 80 contact, the positive interaction of the parts being secured of segmental gear teeth 12 and 13. A retaining ear or keeper 14 is formed on one of the members 11 in such relation thereto that when the parts are forced inwardly past the line of the pivot portions 11 the keeper tends to keep an inserted member, as for example, a striker 15 which is mounted by a suitably designed portion base 16 on the closure or door 17 to which 90 the latch is applied. A longitudinal slot 24 is formed in the casing to clear the keeper 14 when the arms are in outwardly projecting relation or in open position as indicated in Fig. 5, in which relation the outer wall 95 of the casing 1 acts as a retainer to limit the movement of the arms. The portions of the spring 9 that extend beyond the pivot bearings 11 are inturned and act as parallel face guides between which the latch members are free to oscillate. The parts are further so proportioned that when the striker is guided into the slot 4 by the converging faces 3 of the guide lugs 2, and is thereby encountered and force the latch members inward against the outwardly yielding arms of the spring, and the door 17 is contacted with the jamb member, the latch members are still clear of the spring or base plate and because of the converging tendency of 110 the spring arms exert an inward pressure upon the striker 15 and thereby close the

joint between the door and the jamb under all normal working conditions.

A handle member 18 on the striker facilitates the operation of the latter and is also 5 in such convenient relation to the casing that in a modified form of the latch wherein one of the latch members has a thumb piece 19 extending through a suitable opening in the casing, the hand of the operator may 10 grasp the handle 18 and with the thumb as a fulcrum pressing against the thumb piece 19 assist materially in unsnapping or releasing the latch members.

In the modification shown in Figs. 6 and 15 7 a link 20 having parallel sides passes through an opening in one of the latch members and plays in a slot 21 in the other acting as a guide to replace the extended portions of the main spring for maintaining 20 the latch members in alined relation.

The casing may be so modified, as shown 25 in Figs. 10 and 11, that holder guide lugs 23 thereon completely house the latch members, the longitudinal slot 24 of the other construction being omitted.

As a result of this construction a latch is obtained that is quickly and readily applied to any door that maintains the door in tightly closed position and that readily 30 yields to a pull so as to release the door without the necessity of turning a handle or throwing a latch bolt.

Obviously, changes in the details of construction may be made without departing 35 from the spirit of my invention and I do not care to limit myself to any particular form or arrangement of parts.

What I claim is:

1. A latch comprising a striker member, a 40 casing having guide lugs for the striker, a spring having oppositely disposed arms mounted in the casing, a pair of oppositely disposed latch plates pivotally engaged at the outer ends in the spring arms respectively, with their inner ends in rolling contact and in the path of motion of the striker, and a keeper on one of the latch plates adapted to retain the striker when the latter has entered the casing and passed the line of 45 the pivot centers of the latch plates, the latter coöperating with the spring to yieldingly force the striker inward when so engaged.

2. A latch comprising a striker, a casing 55 provided with guiding means for receiving the striker, a spring member in the casing having a pair of oppositely disposed arms, a pair of oppositely disposed latch members pivotally and detachably interlocking with the spring arms near the outer ends and in 60 rolling contact near their inner ends which lie in the path of the striker, a keeper on one of the latch members for engaging the striker, the latch members and spring coöperating 65 to yieldingly maintain an inward pres-

sure on the striker when the latter has passed the line of pivotal connections between the spring and the latch members, and means in sliding engagement with the latch members for maintaining them in 70 alined relation.

3. A latch comprising a striker, a casing having guiding means and a receiving slot for the striker, a spring in the casing having oppositely disposed arms, latch plates 75 each bearing against a spring arm near the outer end and in rolling contact at the inner ends thereof, substantially in the path of the striker, and a keeper for engaging the striker, adapted to coöperate with the arms 80 and spring to force the striker yieldingly inward when it has passed the line of attachment of the latch plates and spring arms.

4. A latch comprising a striker, a casing having a receiving slot therefor, guide projections on the casing adjacent the slot, a spring secured between its ends in the casing and provided with oppositely extending arms, and a pair of latch plates detachably fulcrumed near their outer ends on the 90 spring arms with their inner end portions in rolling contact and in the path of the striker, said arms being adapted to grip an inserted striker and force it yieldingly inward when the striker has passed the line of 95 pivotal attachment of the latch plates and springs.

5. A latch comprising a striker, a casing having a receiving slot therefor, guide projections on the casing adjacent the slot, a 100 spring secured between its ends in the casing and provided with oppositely extending arms, a pair of latch plates detachably fulcrumed near their outer ends on the spring arms with their inner end portions in rolling contact in the path of the striker, said arms being adapted to grip an inserted 105 striker and force it yieldingly inward when the striker has passed the line of pivotal attachment of the latch plates and springs, 110 and a thumb piece on one of the latch members extending through the casing on the side of the latch plate fulcrum opposite the guide slots.

6. A latch comprising a striker, a casing 115 having a receiving slot for the striker, and guiding means for the striker adjacent the slot, a bed plate in the casing, a spring member attached to the bed plate and provided with oppositely extending arms embracing 120 the guide slot, a pair of latch plates removably fulcrumed near their outer ends on the spring arms with the inner end portions thereof in rolling contact and in the path of the striker, the length of the arms being greater than the normal distance between the points of pivotal connection with the spring, and a keeper carried by the latch plate and adapted to coöperate with the latch plates to grip and force the striker 125 130

yieldingly inward when the latter has passed the line of pivotal connections between the latch plates and spring arms.

7. A latch comprising a striker, a casing provided with a guide way for receiving the striker, a spring mounted in the casing having oppositely disposed longitudinally slotted arms each with an enrolled middle tongue forming a fulcrum bearing, a pair of latch plates each seated at its inner end against the fulcrum of a spring arm between the outer arms thereof, the outer end portions of the latch plates being in rolling contact and in the path of the striker, and a keeper for retaining the striker against the latch plates and forcing the striker inward when the latter has passed the line of the spring fulcrums.

8. A latch comprising a striker, a casing having a receiving slot for the striker, a pair of oppositely disposed guide members for directing the striker into the slot, a spring member secured between its ends in the casing and provided with oppositely disposed arms, a longitudinal tongue formed from each arm and inrolled as a fulcrum bearing, a pair of latch plates, the inner end faces of which are arranged to rock upon the fulcrum bearings and between the outer portions of the spring arms, the outer end portions of the plates being in rolling engagement and in the path of the striker, and a keeper for retaining the striker against the latch plates and coöperating with the spring and latch plates to force the striker inwardly when it has passed the line of fulcrum bearings.

9. A latch comprising a striker, a casing having a receiving slot for the striker, a pair of oppositely disposed guide members for directing the striker into the slot, a spring member secured between its ends in the casing and provided with oppositely disposed arms, a longitudinal tongue formed from each arm and inrolled as a fulcrum

bearing, a pair of latch plates, the inner end faces of which are arranged to rock upon the fulcrum bearings and between the outer portions of the spring arms, the outer end portions of the plates being in rolling engagement and in the path of the striker, a keeper for retaining the striker against the latch plates and coöperating with the spring and latch plates to force the striker inwardly when it has passed the line of fulcrum bearings, and means loosely embracing the free arms of the latch members and maintaining them in alined relation.

10. A latch comprising a striker provided with a handle and adapted to be secured to a closure, a casing provided with a guide-way for receiving the striker and adapted to be secured to a frame member for the closure, a bed plate mounted in the casing, a spring member secured between the oppositely curved slotted end portions thereof to the bed plate, a latch plate fulcrum on each arm of the spring bridging a longitudinal slot therein, a pair of oppositely disposed latch plates with the inner ends thereof rocking against the fulcrums between the side portions of the spring arms, the outer end portions of the latch plates being in rolling contact and in the path of the striker, a keeper on one of the latch plates adapted to grip the striker and to coöperate with the spring arms and latch plates to force the striker inwardly when the latter has passed the line of the spring fulcrums and a thumb piece extending from the pivot end of one of the latch plates through an opening in the casing in manually operative relation to the handle of the striker.

In testimony wherof I affix my signature in presence of two witnesses.
